(57) **CLAIM**

The ornamental design for a Motion Sensor Light as shown and described.

DESCRIPTION

FIG. 1 is a perspective view of a motion sensor light, as viewed from the top and front.

FIG. 2 is a front profile view thereof.

FIG. 3 is a back profile view thereof.

FIG. 4 is a side profile view thereof.

The broken lines in the drawings illustrate portions of the motion sensor light that form no part of the claimed design.
